UNITED STATES PATENT OFFICE.

STEPHEN S. HOLT, OF SUPERIOR, WISCONSIN.

FILM-REWINDING MACHINE.

1,361,860.

Specification of Letters Patent. Patented Dec. 14, 1920.

Application filed June 26, 1919. Serial No. 306,935.

To all whom it may concern:

Be it known that I, STEPHEN S. HOLT, a citizen of the United States, residing at Superior, in the county of Douglas and

5 State of Wisconsin, have invented certain new and useful Improvements in Film-Rewinding Machines, of which the following is a specification, reference being had therein to the accompanying drawing.

10 This invention relates to certain improvements in rewinding devices and has special reference to a machine for rewinding moving picture films.

It is well known to those versed in the art that a film in the common moving picture machine is usually led from a spool or reel above the machine to a similar reel below the machine, the leading end of the film being connected to the hub of the 15 lowermost reel after being passed through the machine and upon which the film is wound after having been exposed and as it passes through the machine. By this process it is evident that the leading or starting end of the film will be at the center of the reel instead of at its peripheral edge which necessitates the film being rewound before it can be again successfully used in a moving picture machine, and it is the 20 principal object of my present invention to provide a simple and positive device for performing this rewinding of such films.

While the embodiment here illustrated is shown as applied particularly to moving picture machine films, it is evident it may be successfully used for the rewinding or winding of other similar rolls of material.

Further objects and advantages of the peculiar construction will appear as the description of the invention proceeds.

In the accompanying drawings forming part of this application and in which like reference characters indicate like parts;

Figure 1 represents a side elevation of one 45 of the improved machines, and

Fig. 2 is an end elevation of same.

1 represents a suitable supporting frame preferably of rectangular form and composed of metal angle bars, the base of which 50 forms a suitable support for an electric motor indicated at 2, and the intermediate horizontal bars 3 which form a suitable support for the winding and controlling mechanism. Adjacent the two ends of the bars 55 3 and transversely thereof, are journaled two shafts 4 and 5, the shaft 4 being the one

upon which the film carrying reel indicated at 6 is placed and the shaft 5 being the one on which the empty reel indicated at 7 is placed for receiving the unwound film from the reel 6 as the machine progresses in its operation. This latter is performed by the motor 2, transmitting power through the endless belt 8 to a sheave 9 keyed upon the shaft 10 suitably journaled longitudinally 60 of the intermediate bars 3. This shaft carries fixed to the end thereof, adjacent the shaft 5, a flat friction disk 11 which frictionally engages a similar though smaller disk 12, which is keyed upon the shaft 5 and 65 by which the latter is driven. The disk 11 is held at all times tightly against the disk 12 by means of the expansive spiral spring 13 encircling the shaft 10 on the opposite side of the sheave 9 to that of the disk 11. 70 A third shaft 14 is mounted transverse and within the intermediate members 3 of the frame and carries upon its outer end on the same side of the frame as the projecting ends of the shafts 4 and 5, a depending arm 75 15, carrying upon its extreme end the flat spool 16 which is designed to rest upon the film as it passes from one reel to the other as indicated in dotted lines Fig. 1. The arm 15 is keyed to the shaft 14 and the latter has 80 fixed thereto within the frame a block 17 carrying an arm 18, which at its extreme free end has attached a rod 19 connected with the arm 20 of a common knife-blade switch indicated at 21. By this attachment 85 when the spool 16 is in its elevated position as shown in dotted lines, the knife-blade switch will be closed and when the spool is in a position shown in full lines, which position it assumes by gravity when not held 90 up by the film, the knife-blade switch will be open and the opening and closing of the switch controls the operation of the motor 2 in the usual manner.

I have shown a brake shoe 22 resting upon 100 a suitable flat pulley 23, fixed to the shaft 4. This shoe is held in position by means of the strap 24 being pivotally attached at 105 25 and governed at its free end by the up-standing screw-threaded rod 26 which carries the expansive spring 27 intermediate of its upper free end and the free end of the strap 24 while a suitable thumb-screw indicated at 28 screw-threadedly surrounds the lower end of the bolt 26 below the bolt support 29 and by which thumb-screw the tension of the spring 27 on the free end of

the strap 24, which indirectly effects the pressure of the shoe 22, may be adjusted as is obvious.

At the opposite end of the frame 1, is 5 pivotally mounted, as at 30, a control lever 31, extending upwardly to a point above the top of the frame and passing adjacent the hub of the friction disk 12. This control lever 31 is pivotally attached to the 10 hub of said disk as at 32, and by which connection the disk 12 may be slid back and forth on the face of the disk 11, thus governing the relative speed of the two disks and their shafts, the operation of which is 15 well known. The upper end of the control lever 31, is held in any desired fixed position longitudinally the shaft 5 by means of a suitable thumb-screw and bolt indicated at 33 and co-operatively engaged within the slot 20 34 in the upstanding angle 35.

When a reel carrying a film is placed on the shaft 4, an empty reel is placed on the 25 end of the shaft 5 with the end of the film applied thereto, when the machine is started by the spool 16 being raised and allowed to rest upon that portion of the film spanning the distance intermediate of the reels. The machine may be thus left running and given 30 no further attention until desired as it will stop automatically by the spool falling when the end of the film is reached as above described.

The tension of the film may be governed by the pressure of the brake shoe 22 on the 35 flat pulley 23 and the speed of the winding shaft 5 may be governed by the adjustment of the friction disk 12 as above described the advantage of all of which will be readily understood by those skilled in the art.

Various modifications in the construction 40 here shown and within the scope of the claim may be resorted to without departing from the spirit of the invention.

Having thus described my invention what I claim as new and desire to secure by Letters Patent, is:

A film rewinding device comprising in combination, an upright rectangularly shaped supporting frame, a reel carrying supply shaft journaled in and transverse 50 one end of the frame, said shaft having in co-operative relation therewith a spring controlled brake shoe, a second reel carrying take up shaft journaled transverse the opposite end of the frame, a counter shaft 55 journaled centrally of the frame, at right angles to, intermediate of and on the same plane with the first mentioned shafts, a motor carried by the frame beneath the shafts and operatively connected with the counter shaft, an electric circuit for the motor, an adjustable transmission connecting the counter shaft with the take up shaft, and a control shaft journaled transverse 60 the frame and beneath the counter shaft, said control shaft carrying means co-operatively engageable with the film being rewound and means automatically controlling the electric circuit to the motor, substantially as described.

70 In testimony whereof I have hereunto affixed my signature in the presence of two witnesses.

STEPHEN S. HOLT.
